UNITED STATES PATENT OFFICE.

WILLIAM A. BRODIE, OF TORONTO, ONTARIO, CANADA.

PROJECTILE FOR BREAKING WIRE ENTANGLEMENTS.

Application filed November 11, 1926. Serial No. 147,660.

The object of the invention is to provide a shell which when directed into an area protected by wire entanglements will engage with the wires and tear down the entanglement in such a manner as to allow the passage of troops through the protected area.

The principal feature of the invention consists in the arrangement of hinged arms within the projectile which when released will 10 extend radially from the projectile to engage and tear down the wire entanglements into which it is directed.

In the drawings, Figure 1 is a longitudinal mid-sectional view of a projectile constructed 15 in accordance with this invention.

Figure 2 is an elevational view of the projectile showing the arms distended.

Figure 3 is a cross section through the line 3—3 of Figure 1.

In the practice of warfare it has been demonstrated that wire entanglements form a very strong and almost impregnable defense which have required vast quantities of high explosive shells to break down to permit 20 the passage of troops and the present invention proposes a very effective means for tearing down such entanglements.

The invention comprises a projectile body 1 which may be of cast metal having a transverse slot 2 formed therein which extends longitudinally of the side walls of the shell forming the channels 3.

A pin 4 of ample proportions extends transversely of the slot 2 and on this pin are 35 pivotally mounted a pair of arms 5, the outer sides 6 of which conform to the contour of the outer wall of the projectile when in the closed position. The arms extend longitudinally of the channels 3 and the extremities 40 thereof are secured by engagement with a flange 7 of the fuse cap 8.

The fuse cap 8 is threaded into the open 45 end of a cavity 9 in the nose end of the projectile which is adapted to contain a suitable quantity of an explosive which when detonated by the fuse will blow off the cap and release the arms 5.

The arms 5 upon being released will by the rotative movement of the projectile be thrown

outwardly and the rotating projectile with 50 the projecting arms striking into a wire entanglement will engage the wires and tear down the structure.

The arms 5 are of a very sturdy structure and material and will effectively resist the impact with the structures encountered. The base end of the projectile is provided with the usual "gas ring" 10.

What I claim as my invention is:

1. A projectile having a rigid cast metal 60 body formed with a cavity for the reception of explosive material in the forward end thereof opening forwardly, arms pivoted to said rigid body and extending forwardly at the sides thereof, means closing the open end of said cavity and engaging said arms to prevent their outward movement, said closing means being adapted to be blown free from the shell cavity to effect the release of the arms and permit the same to swing outwardly 65 through the rotative action of the projectile in flight, the walls of said cavity confining the force of the explosion laterally to shield the arms therefrom.

2. A projectile having a rigid body formed 70 with longitudinally extending slots in opposite sides thereof diverging toward the forward end and having a central intact portion between said slots, a cavity adapted to contain explosives formed in said intact portion and being open only at the forward end, the 75 wall of said cavity being adapted to resist the lateral force of explosion, arms arranged in said slots pivotally connected at their rear end to said rigid shell body and having their forward ends terminating adjacent the open end of said cavity, and a fuse cap threaded into and closing the forward end of said shell cavity and engaging the adjacent ends of said arms to normally prevent their outward 80 movement, said cap being adapted to be blown free from the shell cavity to permit said arms to be extended laterally through the 85 centrifugal action of the rotating shell independent of the explosive force within said cavity.

3. A projectile having a rigid cast metal body formed with a diametrically disposed

slot extending transversely from side to side thereof and channels extending longitudinally, forward from said slot on opposite sides thereof, a pin extending diametrically 5 of said shell transversely of said slot, a pair of arms each hinged on said diametrically arranged pin and housed in said slot and channels, means mounted on said rigid shell body

and engaging the forward ends of said arms to secure the latter in the channels, and means for breaking said engagement to effect the release only of said arms during the flight of said projectile to permit the arms to extend laterally outward by centrifugal force due to the rotative motion of the projectile. 10

WILLIAM A. BRODIE.
